UNITED STATES PATENT OFFICE.

EUGÈNE SCHNEIDER, OF PARIS, FRANCE, ASSIGNOR TO SCHNEIDER & CIE., OF PARIS, FRANCE, A LIMITED JOINT STOCK COMPANY OF FRANCE.

APPARATUS FOR REGULATING THE COMBUSTION IN FUSES FOR SHELLS.

1,310,895.

Specification of Letters Patent. Patented July 22, 1919.

Application filed August 21, 1918. Serial No. 250,870.

To all whom it may concern:

Be it known that I, EUGÈNE SCHNEIDER, a citizen of the French Republic, and a resident of 42 Rue d'Anjou, Paris, France, have 5 invented a new and useful Improvement in Apparatus for Regulating the Combustion in Fuses for Shells, which invention is fully set forth in the following specification.

This invention relates to time fuses, and 10 particularly to devices for controlling the escape of gases therefrom.

As is well known, time fuses are provided with vents or orifices for the escape of the gases generated by the combustion of the 15 fuse composition, the latter being generally accommodated in rings or plates.

With fuses heretofore in use, it has been extremely difficult to determine in a satisfactory manner the proper size or cross-section of the escape orifices for assuring a 20 regular and certain combustion. More particularly, when it is desired to use one and the same type of fuse for firing at elevations differing considerably from one another, it 25 has been found that a size of the orifices which is suitable for firing the gun at low elevations is very defective when the gun is fired at high elevations, and in such cases premature extinguishing of the fuse is very 30 frequent.

Numerous causes, among which may be mentioned variations of barometric pressure and variations of temperature at different points of the trajectory of the projectile, variously affect the rapidity of combustion of the 35 fuse composition. Therefore, a size of opening which would be suitable for the escape of the gases at any elevation of the gun in that portion of the trajectory that is near

40 the muzzle of the gun, where the projectile is still subjected to a relatively high pressure, generally becomes gradually too great as the pressure acting upon the projectile diminishes irrespective of the causes of such 45 diminution.

It is obvious that it would be extremely difficult if not impossible, to predetermine the size of opening for the escape of the gases which would be suitable, under the 50 varying conditions of pressure, throughout the trajectory.

The present invention has for its object to provide an improved apparatus which provides an automatic regulation of the size of 55 opening for the escape of the gases in ac-

cordance with the variations in the pressure acting upon the projectile at different points of its trajectory.

The improved apparatus consists essentially of a valve or damper adapted to control the escape orifice or orifices formed or provided in the body of the fuse, said valve being so constructed that it is subjected both to the variable pressure acting upon the projectile and to an opposing force produced, 60 for instance, by a suitably adjusted spring. It will be perceived that by adjusting the position of the valve and the opposing force in such a manner that, before firing, the valve uncovers little or nothing of the escape orifices, whereas on coming under the influence of the pressure in the neighborhood of the muzzle of the gun, it uncovers them completely, the mobility of the valve permits the latter to assume during the 65 flight of the projectile, for intermediate values of the pressure acting upon the projectile, corresponding intermediate positions to which will correspond openings of 70 different size for the escape of the gases. In 75 other words, the size of the opening for the escape of the gases will always depend upon the pressure acting exteriorly upon the projectile.

The invention is capable of receiving a 80 variety of mechanical expressions, two of which are shown on the accompanying drawings, but it is to be expressly understood that the drawings are for purposes of 85 illustration only and are not to be construed 90 as a definition of the limits of the invention, reference being had to the appended claims for that purpose.

In these drawings:-

Figures 1 and 2 are longitudinal sections 95 of one embodiment of the invention, showing two extreme positions of the movable valve; and

Fig. 3 is a longitudinal section of a modification, the movable valve being shown in 100 its position of rest.

Referring to the drawings, the usual orifices *b* for the escape of the gases from the fuse body may be formed in the usual manner in a kind of lantern *B* fixed to the fuse 105 body *A* or in any other suitable part fixed to the latter.

Upon, or in this lantern, there is mounted the longitudinally movable valve member *C* which is provided with an internal projec- 110

tion C¹ (Figs. 1 and 2), or an external projection C¹ (Fig. 3), which serves to guide and limit the movement of said valve by coaction with a corresponding groove B¹ 5 provided in the lantern B.

An element C² of the movable valve is arranged to receive externally the action of the variable pressure to which the projectile is subjected during flight, while the 10 valve is also subjected to an opposing force shown as exerted, for example, by a spring D which bears at one end upon a fixed part of the fuse or projectile and at its other end upon the valve. The valve is provided with 15 orifices c equal in number to the orifices b and adapted to be moved into and out of register with the latter.

In Figs. 1 and 2, wherein the valve is shown as positioned exteriorly of the lantern, the element C² may take the form of a cap suitably attached to the sleeve-like body of the valve, as by screw-threaded engagement therewith. In Fig. 3, wherein the valve is shown as positioned interiorly of 25 the lantern, the valve and element C² may be made in one piece. In the latter modification, the lantern is provided with a removable annular end-piece which admits pressure to the element C², said end-piece being 30 shown as in screw-threaded engagement with the body of the lantern.

In its state of rest (Fig. 1), the valve C is caused by the action of the spring D to take a position such that its imperforate 35 portion partially covers the orifices b. By the action of the maximum external pressure to which the projectile is subjected (Fig. 2), the valve is moved into a position in which it entirely uncovers the orifices b. During 40 the flight of the projectile the valve assumes different intermediate positions which correspond to the pressure acting upon the projectile.

It is to be understood that the lantern B 45 and valve C may be provided with any suitable device which would permit regulation of the tension of the spring D when assembling the fuse.

Instead of regulating the escape of the 50 gases by means of the movable valve and a device for opposing movement thereof of the type here shown, wherein a movable perforate member moves with respect to a fixed perforate member, the desired regulation 55 may be effected by any other suitable valve, such for instance as a tapering spindle or a needle movably mounted in an escape conduit.

While the illustrated embodiments have 60 been described with considerable particularity, it is to be expressly understood that the invention is not to be limited to the forms shown, as the same is capable of receiving a variety of mechanical expressions. 65 Reference is to be had to the appended

claims for a definition of the limits of the invention.

What is claimed is:—

1. In apparatus for regulating the combustion of the fuses of projectiles, in combination with the fuse body provided with one or more orifices for the escape of the gases, a valve controlled by the exterior pressure to which the projectile is subjected during its flight for regulating the size of said 75 orifice.

2. In apparatus for regulating the combustion of the fuses of projectiles, in combination with the fuse body provided with one or more orifices for the escape of the 80 gases, a valve controlled by the exterior pressure to which the projectile is subjected during its flight for regulating the size of said orifice, and means for opposing movement of said valve by said exterior pressure. 85

3. In apparatus for regulating the combustion of the fuses of projectiles, in combination with the fuse body provided with one or more orifices for the escape of the 90 gases, a valve member provided with one or more orifices adapted to register with the first-mentioned orifices and adapted to be moved to vary the size of the first-mentioned orifices by the pressure to which the projectile is subjected during its flight. 95

4. In apparatus for regulating the combustion of the fuses of projectiles, in combination with the fuse body provided with one or more orifices for the escape of the 100 gases, a valve member provided with one or more orifices adapted to register with the first-mentioned orifices and adapted to be moved to vary the size of the first-mentioned orifices by the pressure to which the projectile is subjected during its flight, and means 105 for opposing movement of said valve member.

5. In apparatus for regulating the combustion of the fuses of projectiles, in combination with the fuse body provided with 110 one or more orifices for the escape of the gases, a sleeve-like valve member provided with one or more orifices adapted to register with said first-mentioned orifices, and an element connected thereto and moved by the 115 pressure to which the projectile is subjected during its flight to move said valve member.

6. In apparatus for regulating the combustion of the fuses of projectiles, in combination with the fuse body provided with one or more orifices for the escape of the 120 gases, a sleeve-like valve member provided with one or more orifices adapted to register with said first-mentioned orifices, an element connected thereto and moved by the pressure 125 to which the projectile is subjected during its flight to move said valve member, and a spring for opposing said movement.

7. In apparatus for regulating the combustion of the fuses of projectiles, in combi- 130

- nation with the fuse body provided with one or more apertures, a valve member movable within said fuse body and provided with one or more apertures adapted to register with said first-mentioned apertures, said fuse body being provided with an opening to permit said valve member to be subjected to the pressure to which the projectile is subjected during its flight.
- 10 8. In apparatus for regulating the combustion of the fuses of projectiles, in combination with the fuse body provided with one or more apertures, a valve member movable within said fuse body and provided with one or more apertures adapted to register with said first-mentioned apertures, said fuse body being provided with an opening to permit said valve member to be subjected
- 15 to the pressure to which the projectile is subjected during its flight, and a spring for 20 opposing movement of said valve member.
9. In apparatus for regulating the combustion of the fuses of projectiles, in combination with the fuse body provided with one or more apertures, a valve member automatically operable during the flight of the projectile to vary the size of said aperture or apertures in accordance with the pressure acting exteriorly on said projectile. 25
- In testimony whereof I have signed this 30 specification.
